CONVERSION OF HYDROCARBON OILS

Lev A. Mekler, Chicago, Ill., assignor to Universal Oil Products Company, Chicago, Ill., a corporation of Delaware

Application September 30, 1932, Serial No. 635,496

14 Claims. (Cl. 196—61)

This invention relates to the conversion of hydrocarbon oils and more specifically refers to an improved method and means for heating hydrocarbon oils to the high temperatures required for their conversion.

I have found in practice that much higher rates of heating may be safely employed in the heating of hydrocarbon oils while the oil is in a substantially liquid state than during the period in which the oil is undergoing vaporization or, stated more generally, sensible heat may be safely applied at a more rapid rate than latent heat of vaporization. When this practice is not followed, as the temperature of the oil increases and evaporation progresses, the remaining liquid becomes progressively heavier and, with high rates of heating and high tube wall temperatures in the fluid conduit, the heavy material which drops out and comes in contact with the hot metal walls is cracked to form excessive quantities of coke and gas, leaving a deposit of carbonaceous material upon the hot tubes. It is my belief that this accounts for most of the coking difficulties encountered in the cracking of relatively light oils, comprising or containing a high percentage of naphthas or other light distillates, wherein substantially complete vaporization or atomization and substantial conversion of the oil is accomplished in the heating coil. However, I have also found that, once evaporation of the oil has been substantially completed, high rates of heating may again be safely employed without encountering coking difficulties and my investigations show, in fact, that during the period in which the vapors are undergoing substantial conversion an appreciable increase in the amount of heat supplied thereto is required to obtain a temperature rise as the oil passes through this portion of the fluid conduit. Otherwise the requirements for the latent heat of conversion may be greater than the heat supplied to the oil and an actual decrease may occur in the temperature of the oil during this heating stage.

It is the purpose of the present invention to provide an improved method and means of heating hydrocarbon oils, based on the above observations, and subjecting them to conversion whereby the oil is first heated at a rapid rate, wherein the initial rate of heating is decreased during the vaporization period and, finally, wherein the rate of heating is again increased during the final heating and conversion period following substantially complete vaporization or atomization of the oil.

While, as above indicated, the features of the present invention are particularly well adapted

to the conversion or reforming of light oils such as naphthas, straight-run gasoline and other light distillates they are not limited to use with any particular type of oil as they may be advantageously employed with any oil when the conversion conditions employed are such that substantially complete vaporization or atomization of the oil is accomplished in the heating coil. 5

The phrase "substantially complete vaporization or atomization of the oil" as used herein, is 10 intended to define a condition of the oil wherein practically the entire mass of the oil is in a completely vaporized state or exists in the heating coil in the form of a mist or fog, so that no detrimental quantity of heavy liquid adheres to the 15 tube walls where it may be highly heated to form coke.

One specific form of improved furnace structure and arrangement of the fluid conduit or heating coil which permits the practice of the 20 features of the present invention is illustrated in the attached diagrammatic drawings which consist of Figures 1, 2, 3 and 4.

Figure 1 is a sectional plan view of a furnace; Figure 2 is a sectional elevation; Figure 3 is a 25 sectional end view and Figure 4 is a flow diagram illustrating a preferred flow of oil through the heating coil of the furnace illustrated in Figures 1, 2 and 3. The entire drawings are diagrammatic and are intended only to illustrate 30 a practical application of the features of the present invention which are not limited to this nor to any other particular type of furnace structure.

Referring particularly to Figs. 1, 2 and 3, the 35 furnace structure proper consists of side walls 1 and 1', front wall 2 and wall 3, floor 4 and roof 5 enclosing a large combustion zone 6.

The furnace is fired with any desired form of fuel by means of burners (not shown) through 40 ducts 7 of firing tunnels 8. Additional ducts 9 are provided in the firing tunnels for the introduction of auxiliary air or steam.

A fluid heating zone 10 is provided adjacent rear wall 3 of the furnace through which hot 45 combustion gases pass to flue 11 and thence to a suitable stack (not shown). A bank of tubes 12 may be provided in this zone which, in the preferred embodiment of the invention, serves only as a preheater section for the recovery of 50 fluid heat from the hot combustion gases leaving the furnace by the raw oil charging stock. The tubes 13 of fluid heating bank 12 may be connected in series, as illustrated in the drawings, by means of suitable return bends or headers 14 55

or, when desired, the tubes of the fluid heating tank may be connected in parallel by well known means, not shown in the drawings.

Two rows 15 and 16 of radiant tubes 17 are provided adjacent the respective side walls 1 and 1' and roof 5 of the furnace. The tubes of row or bank 15 are exposed to direct radiation from the flame in combustion zone 6 and are termed exposed radiant tubes while the tubes of row or bank 16 are partially shielded by the tubes of bank 15 and are therefore termed shielded radiant tubes but are exposed to some direct radiation from the flame and also to reflected radiation from the side walls and roof of the furnace. The upper portions of side walls 1 and 1' are preferably recessed, as indicated in the drawings, at points 18 and 18', permitting the side wall tubes in rows 15 and 16 to be set back out of the combustion zone in order to prevent direct impingement of flame from the firing tunnels upon these tubes. The tubes of radiant banks 15 and 16 are preferably connected in series, as illustrated in the drawings, by means of suitable return bends or headers 19. A single row 20 of radiant floor tubes 21 is provided, in the furnace here illustrated, adjacent floor 4. More than one row of floor tubes may, of course, be employed, when desired. The floor 4 is preferably depressed ahead of firing tunnels 8, as indicated at 22 in the drawings to prevent flame impingement on the tubes of the radiant floor bank 20. Tubes 21 of bank 20 are also preferably connected in series by means of suitable return bends or headers such as illustrated, for example, at 23.

Referring to Figure 4 which is a flow diagram illustrating a preferred hook-up for the flow of oil through the entire heating coil or fluid conduit of the furnace structure, as illustrated in Figures 1, 2 and 3. The heating coil consists, as already described, of preheating or convection bank 12, exposed radiant bank 15, shielded radiant bank 16 and the radiant floor bank 20. As indicated by the direction of the arrows in Figure 4, the oil enters fluid heating or preheating bank 12, flowing through the tubes of this bank in series, countercurrent to the flow of combustion gases, the preheated oil flowing then through the tubes of the exposed radiant bank 15 in series, where it is heated at a high rate of heat input, then passing through the tubes of shielded radiant bank 16 in series, where it is heated at a lower rate, and, finally, passing in series through the tubes of radiant floor bank 20 where it is again heated at a rapid rate, from which the heated oil leaves the heating coil to other portions of the cracking apparatus, not illustrated.

It will be understood that it is not only possible to employ different types of furnace structures and heating coils than illustrated in the drawings, but it is also possible to employ different flows through the particular heating coil shown without departing from the scope of the invention, the object of the invention being to heat the oil first at a rapid rate, prior to any substantial vaporization thereof, then to heat the oil at a lower rate during the vaporization period and finally to heat the oil again at a rapid rate, after vaporization or atomization has been substantially completed.

As an example of another possible flow, not illustrated in the drawings, with the same heating coil as that shown, the oil may be first preheated in fluid heating bank 12, may then pass through radiant floor bank 20, then through

the shielded bank of tubes 16 and finally through the exposed bank of radiant tubes 15.

As a specific example of conditions typical of the present invention under which an oil may be treated in the various portions of the heating coil above illustrated and described, the oil may enter the convection or preheater section at a pressure of about 800 pounds per square inch and may be heated therein at a rate of approximately 5000 B. t. u.'s per square foot of circumferential tube area, leaving the preheater section to enter the exposed radiant wall and roof tubes at a temperature of about 750° F., and being heated in this portion of the heating coil, at the rate of about 12,000 B. t. u.'s per circumferential square foot of tube surface, to a temperature of about 875° F. The oil then passes through the shielded radiant wall and roof tubes where it is heated at the rate of about 6,500 B. t. u.'s per circumferential square foot of tube surface to a 20 temperature of about 925° F., finally passing through the radiant floor tubes, where a heating rate of about 13,000 B. t. u.'s per circumferential square foot of tube surface is employed, leaving the furnace at a temperature of about 975° F., 25 and a pressure of about 400 pounds per square inch.

Under these conditions a Pennsylvania naphtha may be cracked to yield as much as 78% of motor fuel having an anti-knock value as high as an octane number of about 78 and the heating coil may be operated over an almost indefinite period of time without experiencing coking troubles as compared with a period of operation of only ten days to two weeks with less favorable heating conditions.

I claim as my invention:

1. In the heating of light hydrocarbon oils of the character of naphtha and gasoline to effect their pyrolytic conversion, the improved method of heating which comprises first subjecting the oil while substantially in liquid phase to heating at a rapid rate, then subjecting the oil to heating at a decreased rate and substantially completely vaporizing it during this heating at the decreased rate and then again heating it at a relatively rapid rate during the final heating and cracking the oil in vapor phase during such final heating.

2. A method of heating light hydrocarbon oil of the character of naphtha and gasoline to effect its pyrolytic conversion which comprises first heating the oil while substantially in liquid phase at a rapid rate to below the point of substantial vaporization, then vaporizing the oil by adding latent heat of vaporization at a decreased rate and finally supplying the heat of cracking to the vapors at a sufficiently high rate to prevent an appreciable decrease in their temperature.

3. In a process for the conversion of light hydrocarbon oil of the character of naphtha and gasoline wherein a continuous stream of oil is advanced progressively through a heating coil and initially subjected therein to a rapid rate of heating while substantially in liquid phase, the improvement which comprises reducing the rate of heat input to the oil during vaporization thereof whereby to minimize the deposition of coke in the heating coil and then cracking the oil in vapor phase by again heating it under a relatively high rate of heat input.

4. A method of heating light hydrocarbon oil of the character of naphtha and gasoline to effect its pyrolytic conversion which comprises passing the oil progressively in a continuous

stream through a heating coil, subjecting it while substantially in liquid phase to a relatively high rate of heating in the initial stages of the heating coil, wherein the major portion of the heat absorbed by the oil is in the form of sensible heat, reducing the rate of heating in that portion of the heating coil wherein the oil undergoes vaporization and wherein the major and final portions of the latent heat required for substantially complete vaporization of the oil is imparted thereto and, finally, heating the vaporized oil at a relatively rapid rate in the latter stages of heating, wherein the final and major portion of the heat of cracking is imparted to the vapors.

5. In cracking petroleum stocks containing a substantial proportion of gasoline for the production of gasoline fractions of improved anti-knock value, the improvement which comprises supplying the stock to a heating conduit substantially in liquid phase, heating the stock to a high cracking temperature in the heating conduit while flowing therethrough as a stream, discharging the heated stock from the heating conduit substantially in vapor phase, and maintaining a 10 lower rate of heat transfer per unit of area of said conduit from a point in advance of that at which substantial vaporization begins to the point at which the phase change substantially ceases than immediately beyond the last mentioned point.

6. In cracking petroleum stocks containing a substantial proportion of gasoline for the production of gasoline fractions of improved anti-knock value, the improvement which comprises supplying the stock to a heating conduit substantially in liquid phase, heating the stock to a high cracking temperature in the heating conduit while flowing therethrough as a stream by heat transferred principally as radiant energy, discharging the heated stock from the heating conduit substantially in vapor phase, and shielding said conduit from the source of said radiant energy from a point in advance of that at which substantial vaporization begins to the point at which the phase change substantially ceases.

7. In the cracking of light hydrocarbon oils which are substantially completely vaporizable under the cracking conditions, the method which comprises heating the oil at a relatively high rate of heat input while substantially in liquid phase, then heating the oil at a lower rate of heat input during vaporization thereof, and, after the oil has been substantially completely vaporized, cracking it in vapor phase by again heating under a relatively high rate of heat input.

8. In the cracking of light hydrocarbon oils which are substantially completely vaporizable under the cracking conditions and wherein the oil is vaporized and then cracked in the vapor phase, the method which comprises heating the oil in liquid phase under a relatively high rate of heat input prior to substantial vaporization thereof, then reducing the rate of heating during vaporization of the oil, and, upon completion of the vaporization, again heating the oil under a relatively high rate of heat input to effect the vapor phase cracking thereof.

9. In the cracking of light hydrocarbon oils which are substantially completely vaporizable under the cracking conditions, the method which comprises supplying the oil to a heating conduit

substantially in liquid phase, heating the oil to a high cracking temperature in the conduit while flowing therethrough as a stream, discharging the heated oil from the heating conduit substantially in vapor phase, maintaining a lower rate of heat transfer per unit of area of said conduit from a point in advance of that at which substantial vaporization begins to the point at which the phase change substantially ceases than immediately beyond the last mentioned point, and subjecting the oil in the initial portion of said conduit and while it is substantially in liquid phase to a higher rate of heating than in the portion of the conduit between said points.

10. The method as defined in claim 9 further characterized in that the oil is subjected to vapor phase cracking conditions beyond said point at which the phase change substantially ceases.

11. In the cracking of light hydrocarbon oils which are substantially completely vaporizable under the cracking conditions, the method which comprises supplying the oil to a heating conduit substantially in liquid phase, heating the oil to a high cracking temperature in the conduit while flowing therethrough as a stream by heat transferred principally as radiant energy, the oil being heated substantially in liquid phase in a portion of said conduit directly disposed to the source of radiant energy, discharging the heated oil from the heating conduit substantially in vapor phase, and shielding said conduit from the source of said radiant energy from a point in advance of that at which substantial vaporization begins to the point at which the phase change substantially ceases.

12. The method as defined in claim 11 further characterized in that the portion of the conduit between said points is shielded from the source of radiant energy by the portion of the conduit in which the oil is heated substantially in liquid phase.

13. In the cracking of light hydrocarbon oils which are substantially completely vaporizable under the cracking conditions, the method which comprises supplying the oil substantially in liquid phase to a heating conduit exposed to radiant heat, vaporizing the oil substantially completely in one portion of the conduit and vapor phase cracking it in a subsequent portion of the conduit, and shielding from the source of radiant heat the portion of the conduit in which the oil undergoes vaporization and change of phase, said subsequent portion of the conduit in which the oil is vapor phase cracked being directly exposed to the source of radiant heat.

14. In the reforming of light hydrocarbon oils containing a substantial proportion of gasoline fractions and which are substantially completely vaporizable under the reforming conditions, the method which comprises supplying the oil substantially in liquid phase to a heating conduit, vaporizing the oil substantially completely in one portion of the conduit and vapor phase cracking it in a subsequent portion of the conduit, supplying heat to the oil in said subsequent portion of the conduit at a relatively high rate of heat input and maintaining a lower rate of heat input in the portion of the conduit in which the oil undergoes vaporization and change of phase.
